UNITED STATES PATENT OFFICE.

HARRY J. SMITH, OF BUFFALO, NEW YORK, ASSIGNOR TO THE ALBERGER COMPANY, OF SAME PLACE.

DESIGN FOR A GAS-ENGINE FRAME OR CASING.

SPECIFICATION forming part of Design No. 34,985, dated August 13, 1901.

Application filed July 21, 1901. Serial No. 66,914. Term of patent 7 years.

To all whom it may concern:

Be it known that I, HARRY J. SMITH, a citizen of the United States, residing at Buffalo, in the county of Erie and State of New York, have invented and produced a new and original Design for a Gas-Engine Frame or Casing, of which the following is a specification, reference being had to the accompanying drawings, forming a part thereof.

This design relates to the configuration of a gas-engine frame or casing.

In the accompanying drawings, Figure 1 is a side elevation of a gas-engine frame or casing embodying my design. Fig. 2 is a top plan view of the same. Fig. 3 is a perspective view of the same. Fig. 4 is an end view of the same.

Like letters of reference refer to like parts in the several figures.

As shown in the drawings, the leading feature of my design consists of the peculiar configuration of the base, cylinders, and valve-chest of the engine.

A represents the base, which consists, essentially, of a wide front pedestal a , a comparatively narrow rear pedestal a' , and a narrow neck a^2 , connecting the front and rear pedestals. The sides of the pedestals and neck slope outward, giving the pedestals a pyramidal appearance. The front pedestal a is provided with a central longitudinal recess B , two circular bearings b , arranged on its

front end on opposite sides of its recess B , and a cylinder-head b' , arranged at its rear end and sloping forwardly along opposite sides of the recess B . One side of the front pedestal is provided with a bearing-bracket C , having a gear-casing c of semicircular form. The opposite side of the neck a^2 is provided with a bracket C' .

D represents the front cylinder, which is arranged horizontally in rear of the cylinder-head b' , D' the rear cylinder, which is arranged horizontally upon the rear pedestal, and d a contracted neck arranged between the front and rear cylinders.

E E' represent valve-chests of rectangular form projecting laterally from the rear part of the cylinders. Each valve-chest has a bearing-hanger e , projecting obliquely downward and outward from its lower side.

The neck d , connecting the cylinders, is provided on its upper and lower sides with longitudinal ribs d' , and the lateral sides of this neck are provided with lateral projections d^2 .

What I claim is—

The design for a gas-engine frame or casing, substantially as herein shown and described.

Witness my hand this 22d day of June, 1901.

HARRY J. SMITH.
